US00D356792S

United States Patent [19]

Murakami et al.

[11] Patent Number: Des. 356,792

[45] Date of Patent: ** Mar. 28, 1995

[54] X-RAY CONTROL BOARD FOR MEDICAL TREATMENT

4,969,167 11/1990 Zupancic et al. 378/19
4,991,193 2/1991 Cecil et al. 378/117
5,272,760 12/1993 Echerer et al. 382/6

[75] Inventors: **Makoto Murakami; Takahisa Yoneyama**, both of Yokohama, Japan

Primary Examiner—Stella Reid
Attorney, Agent, or Firm—Oblon, Spivak, McClelland,
Maier & Neustadt

[73] Assignee: **Kabushiki Kaisha Toshiba**, Kawasaki, Japan

[57] **CLAIM**

[**] Term: **14 Years**

The ornamental design for an x-ray control board for medical treatment, as shown and described.

[21] Appl. No.: **11,231**

DESCRIPTION

[22] Filed: **Jul. 30, 1993**

[30] Foreign Application Priority Data

Apr. 1, 1993 [JP] Japan 5-9362

[52] U.S. Cl. **D24/158**

[58] Field of Search D24/158; 378/208, 204,
378/193, 195, 162, 117, 116, 115, 114, 19;
128/653.2; 382/6.4, 54, 51, 48; 250/322;
D14/103, 104

FIG. 1 is a front, top and right side perspective view of an x-ray control board for medical treatment, showing our new design;

FIG. 2 is a front elevational view thereof;

FIG. 3 is a right side elevational view thereof;

FIG. 4 is a top plan view thereof;

FIG. 5 is a rear elevational view thereof;

FIG. 6 is a left side elevational view thereof;

FIG. 7 is a bottom plan view thereof;

FIG. 8 is an enlarged cross-sectional view taken along line 8—8 of FIG. 2; and,

FIG. 9 is a reduced front elevational view thereof, the broken line showing is for illustrative purposes only and forms no part of the claimed design.
